UNITED STATES PATENT OFFICE

148,120

DESIGN FOR A BILLIARD TABLE OR THE LIKE

Robert I. Anderson, Grand Haven, and Bert Hoeker, Muskegon, Mich., assignors to The Brunswick-Balke-Collender Company, Chicago, Ill., a corporation of Delaware

Application March 13, 1946, Serial No. 127,448

Term of patent 14 years

(Cl. D34—3)

To all whom it may concern:

Be it known that we, Robert I. Anderson and Bert Hoeker, both citizens of the United States, and residents, respectively, of Grand Haven, in the county of Ottawa, State of Michigan, and of Muskegon, in the county of Muskegon, State of Michigan, have jointly invented a new, original, and ornamental Design for a Billiard Table or the like, of which the following is a specification, reference being had to the accompanying drawing forming a part thereof.

The figure is a perspective view of a billiard table or the like embodying our new design.

We claim:

The ornamental design for a billiard table or the like, as shown.

ROBERT I. ANDERSON.
BERT HOEKER.
